UNITED STATES PATENT OFFICE.

AUGUST MÜLLER, OF STRASSBURG, GERMANY.

DESIGN FOR A BOX.

40,506.

Specification for Design.

Patented Feb. 8, 1910.

Application filed November 2, 1909. Serial No. 525,967. Term of patent 7 years.

To all whom it may concern:

Be it known that I, AUGUST MÜLLER, a subject of the Emperor of Germany, residing at 34 Oberlinstrasse, Strassburg, Alsace, German Empire, have invented a new, original, and ornamental Design for Boxes, of which the following is a specification, reference being had to the accompanying drawing, forming a part thereof.

Figures 1 and 2 of the drawings show

the box in front and rear perspective respectively and illustrate my new design.

I claim:

The ornamental design for a box, as shown.

AUGUST MÜLLER.
